REVERSIBLY DRIVEN SWATHER
ATTACHMENT

John Page, Jr., Glidden, Saskatchewan, Canada

Application March 30, 1950, Serial No. 152,821

2 Claims. (Cl. 198—102)

1

My invention relates to new and useful improvements in swather attachments, an object of my invention being to provide a device of the character herewithin described whereby single or double swaths may be laid down by a single machine instead of using two machines as heretofore.

A further object of my invention in conjunction with the foregoing object is to provide a device of the character herewithin described whereby the operator can select a single swath when the yield of grain is heavy or a double swath when the yield is light thereby enabling an associated combine to work efficiently at all times.

Another object of my invention is to provide a device of the character herewithin described whereby the change from single to double swath-laying or vice versa can be made by the operator without stopping the machine.

A yet further object of my invention is to provide a device of the character herewithin described which is particularly suitable for attachments to conventional swathers, and which does not increase the width of said machines to any material extent.

A further object of my invention is to provide a device of the character herewithin described which is relatively light in weight and is easily attached and detached to conventional swathers.

A still further object of my invention is to provide a device of the character herewithin described which may be driven from any convenient source of drive upon existing swathers.

Yet another object of my invention is to provide a device of the character herewithin described which is relatively simple in operation, economical in manufacture, and otherwise well suited for the purpose for which it is designed.

With the foregoing objects in view, and such other objects and advantages as will become apparent to those skilled in the art to which this invention relates as this specification proceeds, my invention consists essentially in the arrangement and construction of parts all as herein-after more particularly described, reference being had to the accompanying drawings in which:

Figure 1 is a top plan view of my device situated upon a conventional swather shown in fragmentary form and with the drive connection to the reel, cutter-bar, and the like deleted for simplicity.

Figure 2 is an enlarged top plan view of my swath-laying conveyor per se.

Figure 3 is a rear end elevation of Figure 2.

2

Figure 4 is a schematic representation of the means provided for selective reversible movement of my swath-laying conveyor but reversed from Figure 3.

Figure 5 is a perspective view of my transfer conveyor per se.

In the drawings like characters of reference indicate corresponding parts in the different figures.

10 In large scale farming, the present practice in harvesting is to use two swathing machines, one being fitted with an extending conveyor in order that the cut grain may be conveyed over onto the swath laid by the first machine travelling in advance, which machine is of standard construction. This entails the use of two operators, two tractors, and two swathers, and the entire field has to be cut in this way resulting in a considerable wastage of man power and effort.

15 Furthermore, this provides a double swath under all conditions which is not desirable inasmuch as when the yield of grain in one particular section of the field is extremely heavy, the combine dealing with this grain is slowed down considerably. However, it is a decided advantage to maintain a double swath where the yield is light so that the combine is provided with sufficient grain for efficient operation.

20 Therefore, I have designed the swather attachment hereinafter to be described which permits single or double swath laying to be undertaken by a single machine at will thereby enabling the operator to select the type of swath to be laid depending upon conditions of yield thus evening up the combine in operation which normally follows.

25 In the accompanying drawings, the conventional portions of the swather have been shown fragmentarily, the various drive means to the components having been deleted for clarity.

30 Proceeding now to describe my invention, it will be seen upon reference to the accompanying drawings that I have provided a substantially rectangular framework 1 mounted upon a shaft 2 supported by ground-engaging wheels 3 only one of which is shown. A conventional reel 4, cutter-bar 5, and main conveyor table 6 are provided and driven from whatever source of power is available to the particular type of swather upon which my attachment is assembled.

35 The main conveyor table 6 operates in a direction of arrow 7 thereby normally depositing cut grain in a swath through a discharge area 8 situated at one end of the aforementioned rectangular framework 1.

Within this area 8 I have provided what I define as a transfer conveyor collectively designated 9 which is adapted to run substantially at right angles to the direction of movement of the main conveyor 6, which conveyor deposits grain upon the transfer conveyor as will hereinafter be described.

The transfer conveyor includes a pair of rollers 10 mounted upon shafts 11 which are journaled for rotation within the rectangular framework 1, the rollers being situated substantially adjacent the forward edge 12 and the rear edge 13 of the main conveyor 6. A further roller 14 is mounted upon a shaft 15 which is journaled for rotation to the rear and above the rear member 16 of the aforementioned rectangular frame 1 as will hereinafter be described. A canvas 17 having conventional slats 18 fixed thereto, extends around rollers 10 and 14 in the form of an endless belt and, due to the positioning of roller 14 in a plane above that of rollers 10, forms a forward portion 19 of the transfer conveyor and a rearward and upwardly extending portion 20 thereof.

The forward portion 19 is substantially parallel although at right angles to the upper run of the aforementioned main conveyor 6 and does not commence to elevate until clear of the rear edge 13 thereof. The rear portion 20 of the transfer conveyor is guided upwardly and rearwardly by means of angle iron guides 21 extending from brackets 22 to spindle 15 upon which the rear roller 14 is mounted.

These guides are curved as illustrated in Figure 5 thus guiding the upper run of the forward end of the conveyor 20 in a gentle curve towards the roller 14.

One end of shaft 15 is extended and provided with a pulley 23 around which a belt 24 extends to a convenient source of driving power (not illustrated) from the main swather.

The rear end 20 of the transfer conveyor or what may be termed the discharge end thereof, overlies my swath-laying conveyor collectively designated 25 and which is situated to the rear of the main swather and substantially towards one end thereof.

This swath-laying conveyor includes a substantially rectangular framework 26 formed by parallel front and rear transverse members 29 and 29' and the rearwardly extending supporting members 27 and 27' which are secured to the rectangular frame 1 of the main swather and provide support to the swath-laying conveyor cantileverwise.

Further support to the swath-laying conveyor is provided by the aforementioned guides 21 of the transfer conveyor 9, the upper ends of which carry shafts 15 of roller 14 which is also journaled for rotation within a pair of brackets 28 secured to the front member 29 of the rectangular framework 26 of the swath-laying conveyor.

The swath-laying conveyor includes a pair of rollers 30 mounted upon shafts 31 journaled for rotation within slots 32 provided within the ends of transverse members 29 and 29' of the rectangular framework 26. A canvas 32' extends around rollers 30 and is provided with slats 33 in the conventional manner and it will be seen from Figure 1 of the accompanying drawings that canvas 32' is substantially parallel to and to the rear of the main conveyor 6.

I have provided means for driving canvas 32' in either direction thereby permitting this con-

veyor to be capable of selected reversible movement as required by the operator of the swather. The means to provide this selected reversible movement is shown in detail in Figures 2, 3 and 4 and includes a main drive-shaft 33 supported for rotation within a bracket 34 extending from member 27 and within a bearing contained in a plate 35 bolted to member 29 of the rectangular framework 26 of the swath-laying conveyor.

A triple sheave-pulley 36 is keyed to this shaft and a belt 37 extends from one of the sheaves to a pulley 38 connected to a further shaft 39 which is an extension of the shaft upon which the inner roller of the main conveyor is secured. This acts as a source of power to the swath-laying conveyor 25.

Pulleys 40 and 41 are keyed to the extremities 42 of shafts 31 carrying rollers 30. A belt 43 extends between pulley 40 and one of the sheaves of the triple sheave-pulley 36, a further belt 44 extending between the other sheave of this pulley and pulley 41. Reference to Figure 4 will show that the latter belt 44 is crossed for the purpose hereinafter to be described.

From the foregoing it will be observed that if pulley 38 is rotating in the direction of arrow 45, the triple sheave-pulley 36 will rotate in the direction of arrow 46. If belt 43 is engaged within sheaves upon pulley 36, then the upper run of canvas 32' of the swath-laying conveyor 25 will move in the direction of arrow 47, or in other words, leftwardly with relation to the remainder of the drawings. Conversely if belt 43 is slackened and belt 44 is tightened, then the upper run of the canvas will move in the opposite direction due to the aforementioned crossing over of belt 44 before passing around pulley 41.

I have provided means for selectively tightening either belt 43 or belt 44 which comprises a lever-arm 48 pivoted at the lower end thereof for partial rotation upon shaft 33, the upper end of this lever extending to a position convenient to the operator of the machine. A cross-bar 49 is situated substantially at right angles towards the lower end of shaft 48 and is provided with a pair of pulleys 50 upon the extremities thereof overlying the upper run 51 of belts 43 and 44, the position of lever 48 determining which belt is engaged by either of the pulleys 50.

Engagement of one of the belts 43 or 44 by one of the pulleys 50 has the effect of tightening this belt thus causing drive to be transmitted from pulley 36 to either pulleys 40 or 41. At the same time as one of these belts is tightened, the opposite one is lifted clear of the sheaves within pulley 36 by means of a depending hook 52 which is mounted upon the extremities of cross-shaft 49 and passes under the upper run 51 of belts 43 and 44 as clearly shown in Figure 3 of the accompanying drawings.

In this connection, reference to Figure 3 will show that shafts 31 together with rollers 32 are provided with tensioning springs 53 which maintain the correct tension upon canvas 32' at all times.

Having described my device in detail its method of operation will now be presented.

The swather is driven by means of a tractor or other similar sources of power in the direction of arrow 54, cut grain being deposited upon the main conveyor canvas 6 which conveys same towards the area 8 as hereinbefore described. The grain is deposited upon the transfer conveyor

which operates in the direction of arrow 55 thus carrying the grain to the rear of the swather and upwardly as shown in Figure 5 depositing same upon the swath-laying conveyor 25. If it is desired to lay the swath to the left of the machine with reference to Figure 1, then lever 48 is moved in the direction of arrow 56 thus causing belt 43 to be tightened by the engagement of pulley 50 with the upper run 51 thereof which causes the upper run of the conveyor canvas to move in the direction of arrow 47. At the same time, hook 52 upon the opposite end of cross-bar 49 lifts the upper run 51 of belt 44 clear of the sheaves thus permitting same to idle.

If it is desired, upon the next round for example, to lay the swath in the same path, then the direction of travel of canvas 32' of the swath-laying conveyor 25 is reversed by moving lever 48 in the direction opposite to arrow 56. This causes pulley 50 to engage the upper run 51 of belt 44 thus tightening same and causing the drive to be transmitted to pulley 41 thus reversing the direction of travel of the canvas. At the same time, the hook 52 upon the opposite end of the cross-bar 49 raises the upper run 51 of the belt 43 thus allowing this belt to idle at this time.

In conclusion, while I have described a belt-driven system for reversing the direction of travel of canvas 32' of the swath-laying conveyor, it will be appreciated that, if desired, a system of drive-shaft and bevel gears, together with a reversing gear-box could be utilized but, for simplicity, the present embodiment is preferred.

Since many modifications can be made in the invention herein described and since the accompanying drawings have been prepared only to illustrate the relative arrangement and interaction of parts and not with regard to accuracy of dimensions for manufacturing purposes which in view of this disclosure I consider to entail merely mechanical skill together with the skill of the mechanical draftsman, and since many apparently widely different embodiments of this invention may be made within the spirit and scope of the accompanying claims without departing from such spirit and scope, it is intended that all matter contained in the accompanying specification shall be interpreted as illustrative only and not in a limiting sense and I desire only such limitations placed thereon as justice dictates.

What I claim as my invention is:

1. A conveyor attachment for swathers and the like, said swather including a conventional main conveyor platform or table and transfer conveyor at right angles thereto, said transfer conveyor including a pair of rollers, an endless canvas rotatable thereon, means for driving one

of said rollers, the forward portion of said transfer conveyor spanning one end of said main conveyor table, the rear portion of said transfer conveyor curving upwardly and rearwardly from the rear edge of said main conveyor table, a swath-laying conveyor at the rear of said swather substantially parallel to said main conveyor table, the rear end of said transfer conveyor being mounted upon the supporting structure of said swath-laying conveyor and overlying said swath-laying conveyor thereby permitting cut grain to be transferred from said main conveyor table and deposited upon said swath-laying conveyor, said swath-laying conveyor including a pair of supporting members extending rearwardly from the main frame of said swathing assembly, a substantially rectangular framework supported by said members, a pair of rollers mounted for rotation within said framework, an endless canvas extending around said rollers, means for driving one of said rollers, said swath-laying conveyor being capable of selective reversible movement, and means to provide said selective reversible movement.

2. The device according to claim 1 in which said means for selective reversible movement of said swath laying conveyor includes a lever, a cross-bar secured to said lever and extending at right angles therefrom, said means for driving said rollers of said swath laying component, including a triple sheave driven pulley, pulleys on the ends of said shafts, a belt extending around one of said sheaves and one of said pulleys, and crossed belt extending around one of said sheaves and of the other of said pulleys, belt engaging sheaves upon each end of said cross-bar, each adapted to engage the upper run of one of said belts thereby tightening same, and hook means depending downwardly from the extremities of said cross-bar and under the upper run of said belts, to lift the upper run of the belt opposite to that which is being tightened thereby loosening same.

JOHN PAGE, JR.
